B. Brey
B. Breyger, Atty.

UNITED STATES PATENT OFFICE.

RALPH SADLEIR FALKINER, OF MELBOURNE, VICTORIA, AUSTRALIA.

CANE-HARVESTING MACHINE.

Application filed January 5, 1926, Serial No. 79,370, and in Australia January 30, 1925.

This invention refers to cane harvesters, as for instance, the kind described in specification Serial No. 744,988, whereby briefly, the cane is cut about the ground level, raised by an elevator and thrown by a pair of pneumatic rollers against a baffle or stop and between a fixed hood and a series of pairs of pneumatic discharge rollers, a pair of rotary cutters operating to sever the tops.

10 The invention consists of certain improvements relating to cane cutting means, air blast means operating in conjunction with a travelling hood to prevent loose or attached trash being gripped by the cane discharge rollers and a series of rollers for discharging the cut cane tops.

The invention is illustrated by the accompanying drawings whereof,

20 Figure 1, is an elevation of the cane harvester with the improvements thereon.

Figure 2, is a fragmentary plan illustrating the cane severing means.

Figure 3, is a vertical section on line III of Figure 1.

25 Figure 4, is an enlarged detail of portion of the travelling hood.

By reference to Figures 1 and 2, of these drawings, it will be seen that a pair of oppositely rotating co-acting cutters 400 are employed to sever the cane about the ground level. These cutters are approximately rectangular but curved at the ends, with two diagonally opposite corners rounded and cutting edges 401 formed at said rounded corners at the curved ends and portions of each side that overlap during rotation of said cutters.

30 Rotation of the cutters is forwardly and outwardly from the longitudinal centre of the machine, i. e. towards the growing cane as indicated by the arrows in Figure 2.

35 The cutters 400 are so set on vertical shafts 402 that one advances at 90° to the other, i. e. one cutter operates one quarter of a revolution ahead of the co-acting cutter so that when one of the cutting edges 401 of one cutter has operated through the cane a corresponding cutting edge of the opposed cutter follows so that said cutters operate alternately.

40 The distance between the centers of said vertical shafts is less than the diameter of the cutters, so that the swath cut by one cutter overlaps that of the other.

45 The shafts 402 are driven by bevel gears

403, 404, 405, from a shaft 406 driven by the engine E, employed to propel the machine.

It is found, with this form of cutter that the cane is successfully cut and breakage through stones choking the cutter is avoided as obstructions met are thrown to one side.

50 In lieu of known stationary hoods arranged over the pneumatic cane discharge rollers 197 and 198, a travelling hood is employed and same consists of slats 413, Figures 1 and 4, attached to a pair of endless belts 414 travelling over pulleys 415, 416 deriving motion from a belt 417.

The under portion of the hood travels in the same direction as the cane and as fast or faster than same so that if the ends of cane shot backwards by the pneumatic throwing rollers 59 and 60 strike the underside of the hood the canes are directed rearwardly against the baffle or stop B.

55 The slats 413 are preferably bevelled on one side as at 418, Figure 4, to prevent the butts of the cane fouling the hood when the tops of the cane strike the baffle or stop B.

60 Side cover boards 430 are provided above the cane discharge rollers 197, 198 to confine the cane and also the air blasts provided to prevent loose trash removed from the cane or still attached thereto being caught between the discharge rollers 197, 198.

65 The blasts of air are delivered between the discharge rollers in an upward and rearward direction through the cane. The air is delivered through outlets 421 extending upwardly as in Figure 1, preferably on the inner sides of the shafts 451 of the discharge rollers 197 and 198, said outlets being connected with pipes 422, that may be rectangular in cross section, leading from two blowers 423 driven by an engine E' that operates 70 the cane throwing rollers 59 and 60 and other parts of the machine.

75 The blasts of air cause the trash on the cane to be blown above the discharge rollers into contact with the rearwardly moving slats 413 of the travelling hood which assists in conveying the loose trash out of the machine at the rear.

80 In addition to the pneumatic discharge rollers two pairs of rotary pneumatic rollers 420 or rollers the outer coating of which is formed of flexible material are mounted on the shafts 451 in a similar manner to rollers 197, 198 and located behind the topping discs 452 mounted also upon said shafts 451, said 85

rollers 420 being employed to discharge the cane tops in a downward direction.

These rollers 420 may have a solid rubber outer coating or a thick outer coating formed of sponge rubber.

I claim:

1. In cane harvesters, a pair of horizontal coacting cane cutters of approximately rectangular shape mounted on oppositely rotating vertical shafts, said cutter rotating forwardly and outwardly and operating alternately with one performing an effective cut a quarter of a revolution in advance of and overlapping the cut of the other.

2. In cane harvesters wherein the cane travels longitudinally thereof, the combination with a series of pairs of downwardly operating cane discharge rollers of a superposed endless travelling hood and means to cause said hood to effectively operate while travelling in the same direction as the cane.

3. In cane harvesters wherein the cane travels longitudinally thereof, the combination with a series of pairs of downwardly operating cane discharge rollers of a superposed travelling hood consisting of belts passing over pulleys and provided with slats, means to cause said hood to travel so that said slats when on the underside travel in the same direction as the thrown cane and at the same speed or faster.

4. In cane harvesters wherein the cane travels longitudinally thereof, the combination with a series of pairs of downwardly operating cane discharge rollers of a superposed travelling hood consisting of belts

passing over pulleys and provided with slats bevelled on one side, said hood travelling in the same direction as the thrown cane.

5. In cane harvesters, the combination with rollers for throwing and for discharging the cut cane, of means to impart air blasts through the cut cane in an upward and rearward direction.

6. In cane harvesters, the combination with rollers for throwing and for discharging the cut cane, of means to impart air blasts through the cut cane in an upward and rearward direction comprising blowers with pipes having outlets located between the discharging rollers.

7. In cane harvesters, the combination with discharge rollers and topping discs of pairs of co-acting discharge rollers for the cut tops located at the rear of said discs.

8. In cane harvesters, the combination with discharge rollers and topping discs of pairs of co-acting discharge rollers for the cut tops located at the rear of said discs, said tops discharge rollers being pneumatic or formed with an outer coating of resilient material.

9. In cane harvesters, the combination with a series of cane throwing and cane discharge rollers and a stop or baffle of a travelling hood above said discharge rollers, side cover boards above said rollers and means for delivering air blasts in an upward and rearward direction through the cut cane.

Dated this seventeenth day of November, 1925.

R. S. FALKINER.
